UNITED STATES PATENT OFFICE.

KARL VON VIETINGHOFF-SCHEEL, OF BERLIN, GERMANY.

AUTOMATIC GAS-LIGHTER.

SPECIFICATION forming part of Letters Patent No. 640,350, dated January 2, 1900.

Application filed August 18, 1899. Serial No. 727,684. (No model.)

To all whom it may concern:

Be it known that I, KARL VON VIETINGHOFF-SCHEEL, a subject of the German Emperor, residing at Berlin, in the German Empire, 5 have invented certain new and useful Improvements in Automatic Gas-Lighters; and I do hereby declare the following to be a full, clear, and exact description of the invention, such as will enable others skilled in the art to

10 to which it appertains to make and use the same.

The present invention relates to improvements in automatic gas-lighters of the kind forming the subject of my previous patent application, Serial No. 695,455, and more especially to arrangements in such gas-lighters by which the lighting device proper is screened against the deteriorating action of the flame.

The invention consists in extending the one leg of the clip carrying the lighting device and 20 forming it into a screen.

The present invention shall now be described with reference to the accompanying drawings, of which—

Figure 1 is a vertical section showing the 25 parts in the position of rest before ignition; Fig. 2, a vertical section through the device, showing the position of the parts after ignition; and Fig. 3, a vertical section showing a modification.

30 *g* is the mica plate, fastened onto the chimney *c* by means of the clip *r* and pivoted to the same at *s*. The mica plate *g* is provided with the aperture *d*. The metal clip *r* likewise carries the lighting device *z* by means of 35 the arm *t*.

The inner leg of the clip *r* is provided with a prolongation *v*, which screens the lighting

device *z* against the action of the flame. This screen is so shaped that the lighting device will not be touched by the flame even 40 when the plate *g* is raised into the position shown in Fig. 2.

In the modification shown in Fig. 3 the lighting device is not suspended from the arm *t* by means of platina wires, but is instead directly fastened to the said arm, the necessary platina wires being in their turn fastened to the lighting device.

Having now particularly described and ascertained the nature of my said invention and 50 in what manner the same is to be performed, I declare that what I claim is—

1. In an automatic gas-lighter, the combination, with the chimney of a gas-burner, of a plate movably hinged on and covering the 55 top of the chimney and provided with an aperture, a lighting device arranged in said aperture, a clip carrying said plate and a screen formed at the inner leg of said clip and extending beneath the said lighting device. 60

2. In an automatic gas-lighter, the combination, with the chimney of a gas-burner, of a clip mounted on said chimney, a plate hinged to said clip and arranged to cover the top of the chimney, said plate having an aperture, a lighting device located in said aperture, and a screen carried by the clip and extending beneath the said lighting device. 65

In testimony whereof I have affixed my signature in presence of two witnesses.

KARL VON VIETINGHOFF-SCHEEL
